APPLICATOR'S GUIDE

Elmer Parkhurst, Indianapolis, Ind.

Application September 9, 1946, Serial No. 695,790

4 Claims. (Cl. 33—187)

1

The present invention relates to an applicator's guide, or more particularly to means for use by the applicator of lapped wall siding, shingles, and the like to assist in supporting the pieces of siding or the like, in proper lapped relation to previously-applied runs thereof, during the operation of securing such pieces to the wall or the like. It is the primary object of the invention to provide means which may be temporarily secured to the wall to which siding is being applied to form a supporting guide upon which pieces of siding to be applied may be supported while the applicator drives the fastening means therefor. A further object of the invention is to provide such a device whose position will be determined in accordance with the location of the upper edge of a previously-applied run of pieces together with the location of the lower edge of the first piece applied to constitute an element of the next succeeding run of pieces, whereby any possible error in the location of one piece or run of material will not be multiplied as the applicator continues with further runs of material. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a more or less diagrammatic elevation, illustrating an embodiment of my invention in use;

Fig. 2 is a section taken substantially on the line 2—2 of Fig. 1;

Fig. 3 is an enlarged side elevational view of one of the hangers forming an element of my invention;

Fig. 4 is a top plan view thereof; and

Fig. 5 is a bottom plan view thereof.

I have shown two elements 10A, 10A of a run of siding or the like which run has already been applied to a wall 33 or the like, and I have shown also one element 10B of the next run of elements to be applied. The run of elements 10B must uniformly overlap the upper edge of the run 10A by an amount indicated at 11; and that degree of overlap must be uniform throughout the run.

In Fig. 1, I have shown two hanger elements 12 and 13 supporting, at its opposite ends, a straight edged bar 14.

Each hanger element comprises an elongated

body 15, provided, at its opposite ends, with one or more threaded sockets 16 and 17. A pair of bolts 18, threaded into the sockets 16, removably secure to the upper end of the body 15 an element 19 provided with a laterally projecting blade or sharpened element 20. That element presents a plane surface 21, substantially perpendicular to the axis of the body 15, and facing in the direction of the opposite end of said body.

Similarly, a pair of bolts 22 fitting in the sockets 17 secure in place upon the opposite end of the body 15 a supporting block 23 presenting a plane surface 24 parallel with, laterally projecting in the same direction, and facing the surface 21. It will be noted that the lateral extent of the surface 24 is somewhat less than that of the surface 21.

The bar 14 will preferably be formed, near its opposite ends, with threaded sockets 25 for the reception of bolts 26, whereby said bar may, if desired, be removably secured to the blocks 23, said bolts passing through smooth bores 27 in the blocks 23.

The distance between the surfaces 21 and 24 of the hanger 12 is precisely equal to the transverse dimension of the straight edge bar 14 plus the desired degree of overlap 11. The distance between the surfaces 21 and 24 of the hanger 13 exceeds the corresponding distance between said surfaces of the hanger 12 by an amount slightly greater than the vertical dimension of the piece 10B reduced by the desired degree of overlap 11.

Thus, if the blade 20 of the hanger 12 is driven into the wall 33 in engaging registry with the upper edge 28 of the piece 10A adjacent one end of the A run, the upper edge 31 of the bar 14 may be moved into coincidence with the lower edge of the piece 10B, and said bar edge 31 will lie in the imaginary line constituting an extension of said edge 29. With the parts so related, the blade 20 of the hanger 13 may be driven into the wall 33 at a point slightly spaced above the upper edge 30 of the piece 10B.

Thus the position of the bar 14 is determined by the relationship between the upper edge 28 of the completed A run and the lower edge 29 of the first piece 10B to be applied to the wall 33.

It will be obvious, and is clearly shown in Fig. 2, that the relationship between the degrees of lateral projection of the surfaces 21 and 24 is such that, when the body 15 is substantially vertical, the block 23 will engage the outer surface of the siding piece 10A while the blade 20 will be driven sufficiently into the wall 33 to provide a solid

2

anchorage for the hanger; and the body 15 will be spaced sufficiently from the wall to accommodate the bar 14.

Each element 19 is formed to provide an additional surface 32 spaced longitudinally beyond the blade 20, extending substantially perpendicular to the plane 21, and located approximately at the root of the blade 20. When the hanger is in anchored position, as shown in Fig. 2, said surface 32 is spaced slightly from the outer surface of the wall 33 to permit the insertion of a suitable tool between the wall and said surface to pry the blade 20 out of the wall when it is desired to remove the guide assembly.

If desired, the bar 14 may be suspended loosely upon the blocks 23; but I believe that it is preferable to have said bars secured to the hanger 12; and, under some circumstances, it is even desirable to have the bar secured to both hangers.

While the primary use for my guide will be, as described above, in properly relating additional runs to one or more previously-applied runs of siding, or the like, it is also useful in properly leveling the lowermost run of siding or the like, which is the one first applied to the wall. For such use, a first piece of siding, or the like, is loosely associated with the wall at a proper level, for instance by driving one nail rather loosely into the wall and through the siding piece at a point near the middle of the upper edge thereof. Now, the bar 14 is brought into contact with substantially the whole lower edge of that siding piece and, with a spirit level supported on the edge 31, that bar (and therefore the lower edge of the siding piece) is brought to an accurately horizontal position. Now, the blade 20 of the hanger 12 is driven into the wall, and thereafter, the operator first being certain that the bar is still accurately horizontal and that its edge 31 coincides accurately with the lower edge of the siding piece, the blade 20 of the hanger 12 is driven into the wall. Thereafter, all of the further siding pieces to form parts of the initial run may have their lower edges supported upon the bar edge 31 before they are secured to the wall, and the lower edge of the run as a whole will therefore be absolutely straight and truly horizontal.

I claim as my invention:

1. An applicator's guide for use in installing lapped siding or the like, including a pair of hangers, each comprising an elongated body, a sharpened element at one end of said body and presenting a plane surface projecting laterally from said body and facing toward the other end of said body, a supporting block at said other end of said body and presenting a plane surface projecting laterally from said body, facing said first-named plane surface, substantially parallel therewith, but of less lateral extent, and a straight-edge bar extending between and supported near its opposite ends upon the plane surfaces of said blocks, the distance between said two plane surfaces of one hanger exceeding the distance between said two plane surfaces of the other hanger by an amount slightly greater than the height of a siding element or the like to be used, reduced by the desired amount of lap.

2. An applicator's guide for use in installing lapped siding or the like, including a pair of hangers, each comprising an elongated body, a sharpened element removably secured to one end of said body and presenting a plane surface projecting laterally from said body and facing toward the

other end of said body, a supporting block removably secured to said other end of said body and presenting a plane surface projecting laterally from said body, facing said first-named plane surface, substantially parallel therewith, but of less lateral extent, and a straight-edge bar extending between and removably secured near its opposite ends upon the plane surfaces of said blocks, the distance between said two plane surfaces of one hanger exceeding the distance between said two plane surfaces of the other hanger by an amount slightly greater than the height of a siding element or the like to be used, reduced by the desired amount of lap.

3. An applicator's guide for use in installing lapped siding or the like, including a pair of hangers, each comprising an elongated body, a sharpened element at one end of said body and presenting a plane surface projecting laterally from said body and facing toward the other end of said body, a supporting block at said other end of said body and presenting a plane surface projecting laterally from said body, facing said first-named plane surface, substantially parallel therewith, but of less lateral extent, and a straight-edge bar extending between and supported near its opposite ends upon the plane surfaces of said blocks, the distance between said two plane surfaces of one hanger exceeding the distance between said two plane surfaces of the other hanger by an amount slightly greater than the height of a siding element or the like to be used, reduced by the desired amount of lap.

4. An applicator's guide for use in installing lapped siding or the like, including a pair of hangers, each comprising an elongated body, a sharpened element removably secured to one end of said body and presenting a plane surface projecting laterally from said body and facing toward the other end of said body, said element further providing a surface spaced longitudinally beyond said plane surface, substantially perpendicular thereto, located near the root of said surface, and facing in the direction of projection thereof, a supporting block at said other end of said body and presenting a plane surface projecting laterally from said body, facing said first-named plane surface, substantially parallel therewith, but of less lateral extent, and a straight-edge bar extending between and supported near its opposite ends upon the plane surfaces of said blocks, the distance between said two plane surfaces of one hanger exceeding the distance between said two plane surfaces of the other hanger by an amount slightly greater than the height of a siding element or the like to be used, reduced by the desired amount of lap.
